UNITED STATES PATENT OFFICE.

JOHN FLOOD, OF NEW YORK, N. Y., ASSIGNOR TO THE FLINTKOTE COMPANY, OF BOSTON, MASSACHUSETTS, A CORPORATION OF MASSACHUSETTS.

ROOF.

Application filed November 16, 1921. Serial No. 515,577.

In the application of roofing material to buildings it is sometimes desirable to apply the roofing in panels or strips of contrasting colors. This invention relates to a method by which this panel effect may be produced readily with strip shingles such as are often constructed of felt impregnated with water or fireproofing material such as asphalt, either with or without a surfacing 10 of ground slate.

Strip shingles as ordinarily constructed are provided with narrow spaced slots extending inwardly from one edge to form tabs which simulate the lower ends of adjacent shingles of a course in appearance. Should adjacent courses of such shingles of contrasting colors be laid in the usual manner the slots being staggered, the color of the lower course of shingles would appear through the slots of the upper course, this causing the color of the upper course to be broken up by streaks of the color of the lower course. To avoid this breaking up of the solid color of the panel a continuous 20 unslotted strip or a shingle strip breaking joints therewith and of the same color is placed beneath the lower course of each panel of the same color so that the color showing between the tabs of this course is the same as that of the panel. It will be noted that this underlying strip is of different edge contour than the superposed roofing material. If desired an increased shadow effect between the panels may be produced by employing for the lower strip underlying the lowest course of each panel, a strip of a shade somewhat darker than that of the panel and permitting it to project somewhat below the lower edge of the tabs 30 of the overlying course.

A pleasing shadow effect may also be produced in a roof of a single color by laying a strip of the same or darker shade beneath the lower end of each course, or at intervals, skipping intermediate courses, the lower edge of the strip either being in alignment with the ends of the tabs of the overlying course, or projecting slightly below according to the effect desired.

For a more complete understanding of this invention together with further advantageous details more especially relative to arrangements of the various courses, refer-

ence may be had to the accompanying drawings in which

Figure 1 is a plan of a strip shingle.

Figure 2 is a plan of a roofing strip which may be used to underlie a course of shingles.

Figure 3 is a plan of a section of roofing laid according to one embodiment of this invention.

Figure 4 is a similar view showing a method by which the shadow effect may be increased.

Figure 5 is a view similar to Figure 3 but showing a manner of employing strip shingles in place of the roofing strips such as shown in Figure 2.

Referring to Figure 1 each strip shingle as ordinarily constructed comprises a strip of roofing material as 1 having a series of spaced substantially rectangular slots 2 extending upwardly from its lower edge to form tabs 3 which simulate the appearance of the butts of ordinary shingles when the strip is laid. At the ends of each strip are formed cutouts 4, the width of which is half the width of a slot so that when the ends of adjacent strips are placed together the continuity of the series of slots 2 appears unbroken.

Referring to Figure 3 the strips are shown as laid in superposed courses, the lower strip being red, the next strip green, the next strip blue black, the next red, the next green and so on. Should these strips be laid in the usual manner with the slots 2 staggered in the adjacent courses it is evident that through the slots of the green course the red shingles beneath would appear, and that similarly through the slots of the blue black the green of the lower course would appear, and through the slots of the red the blue black of the underlying course would appear, this breaking up the solid color of each strip. In order to avoid this a strip of roofing material of a width sufficient to bridge the slots and of the same color as the overlying course may be placed beneath the lower edge of each course where a change in color is made. For example, as shown in Figure 3 a red strip 5 is placed beneath the lower edge of the course of red shingles thus showing red through the slots thereof, a green strip 6 is placed below the course of green shingles to show green through the

slots thereof, and a blue black strip 7 is placed below the course of blue black shingles to show blue black through the slots thereof. While in this figure adjacent courses of contrasting colors are shown, several adjacent courses may be of the same color as shown in Figure 4. In this case it is only necessary to employ the additional roofing strip beneath the lowest course of each group of the same color, since above this lower course the color appearing through the slots of an overlying course is the same as that of the course.

In Figure 4, however, a slight modification is shown in which the strips of roofing material 8 are preferably of a shade somewhat different such as darker than that of the overlying course and the lower edge thereof projects somewhat below the edge 20 of this course. When the strips are laid in this fashion the color showing between the slots appears of a darker shade and enhances the shadow effect giving an appearance of increased thickness to the course. 25 This effect is heightened by permitting the underlying strip to project slightly below the lower edge of the course less than the length of the shingle butts exposed to the weather but throughout their entire extents. 30 This effect is sometimes desirable when a roof of a single color is employed, it being sometimes desirable to place a strip beneath each course, in which case each course appears to be of increased thickness, or it may 35 be desirable to use this strip under certain courses only, omitting the strip under the intermediate courses, this producing a panel effect to the roof in a single color.

In Figure 5 is shown a slight further modification in which instead of using the uncut strips such as 5, 6, 7, and 8 strip shingles may be employed for the underlying roofing material. It is essential, however, that the slots therein should break joints 45 with those of the overlying courses. In order to insure this it may be desirable to invert the underlying strip shingle as shown at 9 in Figure 5 so that the slots as at 2' therein may underlie the solid portion of the 50 overlying strip. Such a construction eliminates the necessity of using roofing material in two different forms and in some cases is preferable on that account since the strips 55 may be used interchangeably as courses in the roof or as underlying strips. These reversely positioned strips may be positioned, if desired, either under each of the courses or skipping several courses and may, if desired, be arranged according to color, as has 60 been above described in connection with the strips 5, 6, 7 and 8.

Having thus described certain embodiments of this invention it should be evident

that many changes and modifications might suggest themselves to one skilled in the art 65 without departing from the spirit or scope of the invention as defined by the appended claims.

I claim:

1. A roof comprising overlapping courses 70 of strip shingles, each strip having spaced slots extending upwardly from its lower edge, and roofing material underlying and projecting below the lower edges of shingles of certain courses in repeated series and 75 throughout their entire extents.

2. A roof comprising overlapping courses of shingles presenting butts spaced by substantially rectangular slots, and roofing material underlying said shingles and said slots 80 and projecting below the butts a distance less than the lengths of said butts exposed.

3. A roof comprising overlapping courses of shingles presenting exposed spaced butts, and roofing material underlying said butts 85 and spaces and projecting slightly below said butts.

4. A roof comprising overlapping courses of shingles presenting exposed spaced butts, and roofing material of a different color 90 shade from said shingles underlying said butts and spaces and projecting slightly below said butts to present a marginal band along the lower ends of said butts and in said spaces presenting a different color 95 shade from that of said butts.

5. A roof comprising overlapping courses of strip shingles, each strip having marginal slots extending from its lower edge, and a strip of roofing material of a darker shade 100 of the same color underlying the lower edge of the strips of certain of said courses and projecting slightly below the same bridging the slots therein and forming a marginal band therebeneath of less width than the 105 exposed portions of said shingles.

6. A roof comprising courses of shingles arranged in groups of different colors, and roofing material of a darker shade of the same color underlying and projecting slightly below the lower edge of the shingles in the lowest course of each group to produce 110 a marginal shadow simulating band therealong.

7. A roof comprising courses of strip shingles arranged in groups of different colors, each strip having spaced slots extending from its lower edge, and a strip of a darker shade and of the same color underlying and exposed along the lower edge of 115 the lowest course of each group and bridging the slots therein.

In testimony whereof I have affixed my signature.

JOHN FLOOD.
